UNITED STATES PATENT OFFICE.

HENRY K. MAYER, OF FORT COLLINS, COLORADO.

MIXING-VALVE.

1,169,666.

Specification of Letters Patent. Patented Jan. 25, 1916.

Application filed June 24, 1914. Serial No. 847,092.

To all whom it may concern:

Be it known that I, HENRY K. MAYER, a citizen of the United States, residing at Fort Collins, in the county of Larimer and State 5 of Colorado, have invented certain new and useful Improvements in Mixing-Valves, of which the following is a specification, reference being had to the accompanying drawings.

10 This invention relates to mixing valves such as are commonly employed upon soda fountains, and has for its primary object to provide a simply constructed and efficient device of this character for mixing two or 15 more different liquids, vapors, or gases which are ejected into a mixing chamber by pressure either naturally or artificially produced.

15 The invention has for another object to provide a valve of the above character which is so constructed that one of the liquids is permitted to flow into the mixing chamber after the several liquids have been mixed together and the other ports cut off, whereby 25 the mixing chamber is cleansed.

20 My invention has for a still further object to provide improved means for regulating the flow of the liquids to the mixing chamber whereby the proportions of the same in 25 the mixture may be varied as desired.

25 With the above and other objects in view, the invention consists in novel features of construction, combination, and arrangement 30 of parts as will be hereinafter referred to 35 and more particularly pointed out in the specification and claims.

35 For a full understanding of the invention, reference is to be had to the following description and accompanying drawings, in 40 which—

45 Figure 1 is a vertical section of a mixing valve embodying my invention in its preferred form; Fig. 2 is a section taken on the line 2—2 of Fig. 1; Fig. 3 is a side elevation 50 of the body with the rotary valve removed; Fig. 4 is a detail face view of the valve disk; and Fig. 5 is a detail section taken on the line 5—5 of Fig. 2.

55 Referring in detail to the drawings, 5 designates the body of the valve which is of rectangular form, and is provided upon its bottom face with a discharge nozzle 6. This nozzle is connected by means of a plurality of ports 7 to the mixing chamber 8 which is 60 formed in one side of the valve body. A horizontally disposed valve shaft 9 is mount-

ed in the body 5, and is provided with an enlarged cylindrical end portion 10 which extends centrally through the mixing chamber. Beyond the enlarged portion 10 of this 60 shaft, the same is provided with a squared or rectangular portion indicated at 11 for engagement in a similarly shaped opening provided in one end of a U-shaped operating arm 12.

65 Upon the inner end of the enlarged portion 10 of the shaft 9, the rotary valve disk 13 is keyed or otherwise secured. The periphery of this valve disk is preferably concave or grooved and the inner face of said 70 disk is recessed to receive a gasket 14 of fiber or other suitable packing material. The valve is provided with a plurality of pins 15 to extend into openings formed in the gasket and prevent rotation thereof with respect to 75 the disk. The wall of the mixing chamber 8 at its outer end is threaded to receive a peripherally threaded circular nut 16 whereby the mixing chamber is closed. This nut is, of course, provided with a central opening 80 to accommodate the enlarged portion 10 of the valve shaft and carries a fiber gasket or washer 17 which surrounds said shaft and prevents leakage. The outer end portion of the enlargement 10 is threaded to receive a 85 nut 18 and the squared end 11 of the valve shaft has a threaded socket to receive the threaded stem of a lock nut 19 which retains the operating arm 12 in connection with said shaft. The opposite end of the valve shaft 9 is also threaded to receive a cylindrical nut 20 which is adapted to be received in a recess 21 formed in the face of the valve body 5. A lock nut 22 is also threaded upon the extreme end of the valve shaft to engage the 90 nut 20 and hold the same in position. Upon the sleeve of this lock nut 22, the other end 95 of the operating arm 12 is loosely engaged.

100 The valve body 5 is provided with the equidistantly spaced fluid inlet ports 23, 24, and 25 respectively, said ports entering through one side of the valve body in a plane at right angles to the shaft 9 and having their inner ends turned and extending in parallel relation to said shaft and opening 105 upon the inner wall of the mixing chamber 8. The rotary valve disk 13 is also provided with inlet ports 26 and 27 respectively. Spaced openings 26' and 27' are formed in the gasket 14 to register with said ports. These 110 ports as well as the fluid supply ports in the valve body have their centers located

the same distance from the axial center of the shaft 9. The ports 26 and 27 in the valve disk, however, are slightly closer to each other than any two of the ports in the 5 valve body, the purpose of which will be later explained. A series of auxiliary ports 28 in the valve disk communicate with each of the openings 26 and 27 and open upon the grooved periphery of said disk. Through 10 these latter ports the liquid is discharged into the mixing chamber 8. The U-shaped arm 12 is centrally provided with a suitable handle indicated at 29 which may be of any desired ornamental form. In order to regulate 15 the flow of the several fluids, I provide the threaded plugs 30 mounted in threaded openings formed in the valve body and communicating with the respective ports 23, 24, and 25. The inner end of each of these plugs 20 is of semi-circular form in cross section or reduced as at 31 so that when the plug is turned to one position, the liquid may flow freely through the port, and upon turning the plug to a greater or less extent, the volume 25 of flow will be reduced accordingly.

Having now described the construction and arrangement of the several features of my invention, its operation will be understood as follows. When the arm 12 is in 30 a vertical position, the ports 26 and 27 are out of registration with the ports of the valve body. When, however, the arm 12 is swung in one direction, the valve disk 13 is rotated and the port 26 brought into registration 35 relation with the port 24 in the valve body while the other port 27 of the disk registers with the supply port 25. Owing to the fact that the ports 26 and 27 are arranged closer to each other than are the ports 40 24 and 25, the port 26 will lap over the port 24 slightly in advance of the registration of the port 27 with the supply port 25. Thus the fluid will be first supplied to the mixing chamber from the port 24, and immediately 45 afterward another fluid will be supplied from the port 25, said fluids being discharged from the auxiliary ports 28 in the valve disk into the mixing chamber and mixed together. After the fluids have thus been mixed, they are discharged through the 50 ports 7 in the valve body from the nozzle 6 thereof. Of course, it will be understood that when the movement of the arm 12 is reversed, the port 27 in the valve disk will first 55 lap over the port 24 in the body 5, and the port 26 will then register with the port 23. When the latter two ports are in full registration, the port 27 in the valve disk is slightly lapped upon the port 24 so that when 60 the arm 12 is moved to shut off the flow of liquid, the port 27 will not be disposed out of complete registration with the port 24, when the flow through the port 23 has been entirely cut off. Thus it will be seen that the fluid entering the valve body

through the port 27 is supplied to the mixing chamber after the mixture is discharged therefrom. Supply port 24 on each movement of arm 12 is first opened and last closed. This additional supply of fluid operates to 70 clean the walls of the mixing chamber whereby the device is maintained in a sanitary condition. By means of the several threaded plugs 30 the proportions of the several liquids entering the mixing chamber 75 may be regulated and varied as desired.

From the foregoing description taken in connection with the accompanying drawings, the construction, manner of operation, and several advantages of my improved 80 mixing valve will be clearly and fully understood.

The device, while of very simple construction, is highly efficient as well as strong and durable in practical use. 85

By means of the valve constructed in the manner above described, the proportions of the several fluids to be mixed may be nicely regulated, and such mixtures rendered uniform. 90

The several parts of the valve may be very easily and quickly assembled or disassembled, thereby further conducing to the maintenance of the device in a thoroughly sanitary condition. 95

While I have above described the preferred form, construction, and arrangement of the several elements employed, it will be understood that the device is, nevertheless, susceptible of considerable modification 100 therein, and I therefore reserve the privilege of resorting to all such legitimate changes as may be fairly embodied within the spirit and scope of the invention as claimed. 105

What is claimed is:

1. A mixing valve for soda fountains comprising a body provided with a plurality of syrup supply ports and a water supply port, said body having a mixing chamber, a rotary valve disk mounted in said chamber and provided with spaced inlet ports to receive syrup from one of the ports in the body and water from another of said ports and separately discharge the same into said mixing chamber, the ports in the valve disk being so spaced with respect to the ports in the valve body that the supply of water to the mixing chamber is continued after the supply of syrup is cut off, whereby the walls of the mixing chamber are cleansed, and means for rotating said valve disk. 110

2. A mixing valve for soda fountains comprising a body provided with a mixing chamber and spaced syrup and water supply ports communicating therewith, a rotary valve member provided with spaced ports to receive syrup and water from the ports in the valve body in a segregated state, 115 120 125 130

said valve disk being provided with a series of relatively small auxiliary ports communicating with each receiving port and adapted to discharge each of the two fluids 5 in a plurality of directions into the mixing chamber, said body having discharge ports for the fluid communicating with said chamber, and means for rotating said valve.

3. A mixing valve for soda fountains 10 comprising a body having a mixing chamber and syrup and water supply ports communicating therewith, a flat rotary disk valve mounted within said chamber and having spaced ports to receive the syrup 15 and water from the ports in the valve body, the ports in said disk being spaced apart to a less extent than the adjacent syrup and water supply ports in the valve body, said disk being further provided with a plu-

rality of relatively small auxiliary ports 20 leading from each of the receiving ports to the periphery of said disk and ejecting the segregated fluids in small streams in a plurality of directions into said mixing chamber, the supply of water to one of the ports 25 in said valve continuing after the supply of syrup to the other port thereof has been cut off, whereby the walls of the mixing chamber will be cleansed, said body having discharge ports communicating with the 30 mixing chamber, and means for rotating said valve disk.

In testimony whereof I hereunto affix my signature in the presence of two witnesses.

HENRY K. MAYER.
